DESIGN FOR AN AUTOMOTIVE PARTS CABINET

Alexander P. Fox, University City, and August
Daniel Reisert, St. Louis, Mo., assignors to
Lincoln Engineering Company, St. Louis, Mo.,
a corporation of Missouri

Application August 23, 1940, Serial No. 94,576

Term of patent 7 years

To all whom it may concern:

Be it known that we, Alexander P. Fox and
August Daniel Reisert, citizens of the United
States and residents of University City, St. Louis
County, Missouri, and St. Louis, Missouri, re-
spectively, have invented a new, original, and
ornamental Design for an Automotive Parts Cab-
inet, of which the following is a specification,
reference being had to the accompanying draw-
ing, forming part thereof, in which

Fig. 1 is a top plan view;
Fig. 2 is a front elevational view; and
Fig. 3 is a side elevational view of an automo-
tive parts cabinet, showing our new design.

We claim:

The ornamental design for an automotive parts
cabinet, substantially as shown.

ALEXANDER P. FOX.
AUGUST DANIEL REISERT.
